WORK ILLUMINATING DEVICE FOR PORTABLE ELECTRICALLY OPERATED CLEANERS

John J. McCabe, Euclid, and Arthur W. Seyfried, Shaker Heights, Ohio, assignors to The Apex Electrical Manufacturing Company, Cleveland, Ohio, a corporation of Ohio

Application December 31, 1936, Serial No. 118,512

3 Claims. (Cl. 240—2)

This invention relates to work illuminating lamps for electrically-operated tools, as for example, suction sweepers and it constitutes a continuation-in-part of our co-pending application, Serial No. 678,454, for Suction Sweeper, now Patent Number 2,099,172, granted Nov. 16, 1937, which was filed in the United States Patent Office on June 30, 1933.

The invention has for its objects the provision of a casing structure which is arranged for the accommodation of a work illuminating lamp; the provision of a guard member for protecting the lamp against injury, the casing structure and guard member having cooperating provisions to permit the ready removal of the guard member whereby access may be had to the lamp; and the provision of built-in means for the accommodation and support of a work illuminating lamp in a device of the class described, which means are designed to enhance rather than to detract from the appearance of the machine.

These and other objects of the invention will become more apparent and better understood after consideration has been given to the following detailed description of the invention taken in connection with the drawings which show, merely by way of illustration, structure adapted for carrying out the objects of the invention.

In the drawings, Figure 1 is an axial sectional view of a suction sweeper illustrating one mode of practicing the invention; Figure 2 is an enlarged detail view of the lamp and its socket; Figure 3 is a detailed sectional view, taken on line 3—3, Figure 1; Figure 4 is a detail sectional view, taken on line 4—4, Figure 2; Figure 5 is a detail sectional view, taken on line 5—5, Figure 2; Figure 6 is a reduced side elevational view of the motor cap of the casing; Figure 7 is a sectional view taken on line 7—7, Figure 8; Figure 8 is a detail side elevational view of a modified form of headlight; Figure 9 is a sectional view, taken on line 9—9, Figure 7; Figure 10 is a sectional view, taken on line 10—10, Figure 7; Figure 11 is a perspective view of the reflector of the headlight shown in Figures 7 to 10; Figure 12 is a reduced side elevational view of the front of a sweeper employing the headlight shown in Figures 7 to 10; and Figure 13 is a reduced side elevational view of the lamp socket employed in the structure shown in Figures 7 to 9.

A suction sweeper, such as shown in Figure 1, has been selected merely for the purpose of illustrating the invention. The appliance shown in this view has a casing comprising an upper exposed shell 1 which defines in part, a chamber for

a brush 2 and a case for a fan 3. An electric motor 4 is provided for driving the brush and the fan. The brush is connected to the motor by means of a belt 5. A wall section 6 cooperates with the shell part 1 to complete the fan chamber and a cover plate 7 cooperates with the wall section 6 to complete the suction chamber. The cover plate 7 is removably held in place by means of a thumb screw 8 and it provides a means for detachably securing a brush guard 10 in place 10 over the suction mouth of the sweeper.

Wheels 11 and 12 are provided for supporting the casing. The motor 4 is enclosed by a motor cap or housing 13 which completes the top part of the casing. The motor 4 is carried on a plate 15 13 and is flexibly secured in the casing by means of rubber gaskets 15 which are clamped between the shell part 1 and the motor housing 13 of the casing. The motor 4 does not contact the housing 13 at any point and because of its flexible securing, it is free to move a slight amount within such housing.

At its forward side, the motor housing 13 is provided with a ledge 16 having an aperture 17 which forms a socket for receiving the neck of an electric lamp 18. The aperture 17 is notched at 20 for receiving the locking pins 21 of the lamp. Beneath the aperture 17 there is located a connector 22 having a pair of lamp engaging contacts 23, adapted to be connected to current supplying conductors 24 which may be connected to the source of current supply for the motor and preferably in series with the motor.

The side of the motor housing behind the lamp 18 is recessed to form a light reflector 25. Grooves are formed at the opposite edges of the reflector 25 for slidably receiving the edges 26 of a lamp guard 27 which is removably secured to the casing by such means. The lamp guard may be provided with light transmitting glass windows 28, as shown in Figure 3, and if desired, the glass panes of the window may, of course, be omitted. The provisions for the work illuminating lamp and its guard are designed so that they may be applied to the casing structure without marring its appearance, and in the present case, the provision of the lamp receptacle and the lamp guard really enhance the appearance of the device by giving the casing a stream-lined appearance.

In the modification of the invention shown in Figures 7 to 13, the lamp is carried by a motor cap or housing 13a similar to the motor housing 13 previously described. In the latter arrangement, a lamp socket 31 is secured in any suitable manner, such as, by bolts 32 to the upper 55

- portion of the forward side of the housing 13a. The lamp socket 31 has a cap portion 31a with downward tabs 31b. The cap 31a forms a protective enclosure for the terminal connections of the lamp and the tabs 31b, which are received in recesses 31c, provide means for rigidly securing the socket parts 31 and 31a to each other. An electric lamp 33 is suspended from the lamp socket 31. Current is furnished to the lamp by way of a cord 34, the strands of which may be connected to the contact members of the lamp socket 31 and to the current supply line of the motor, as previously described in connection with the form of the invention shown in Figure 1.
- 15 The bolts 32 are also used to secure the upper end of a sheet metal reflector 35 in place behind the lamp 33. The lower end of the reflector is secured to the motor housing by any suitable means, such as drive screws 36. The vertical edges 37 of the reflector cooperate with the side of the motor housing to form guide slots for a pair of guide plates 38 which are secured by means of rivets or drive screws 40 to an apertured lamp guard member 41. Because of the provision just described, the guard member 41 may be detached from the motor housing 13a in much the same manner as for the guard member 27.

In the modification shown in Figures 7 to 10, the location of the lamp socket above the lamp instead of below it, permits the concealing of the socket beneath the imperforate top part of the guard member 41 and this form of construction also permits the full use of the illuminated portion of the lamp. In addition to enhancing the appearance, the locating of the socket in the position shown, permits the suspending of the lamp from its socket end, and in devices such as the type shown, which are subject to considerable vibration, it has been found that the life of the lamp is increased when it is mounted in this manner.

While it is preferred to mount the lamp with its axis substantially vertical, it is to be understood that the lamp may be mounted with its axis horizontally disposed, in which case the lamp socket would be positioned at one side of the reflector instead of at the top or bottom as shown and the dimensions of the casing parts about the lamp would be changed slightly to accommodate the lamp and its socket when mounted in this manner.

The foregoing description and the accompanying drawings to which it relates, describe what might be termed the preferred modes of practicing the invention. It is to be clearly understood, however, that the invention includes each and every novel feature or combination of novel features herein disclosed, subject only to the restrictions of the prior art, and that the invention may assume other forms and it is not to be

limited to the particular and specific structure shown and described herein.

Having thus described our invention what we claim is:

1. In a portable suction cleaner, a casing structure defining a suction nozzle and a substantially closed motor housing located rearwardly of the suction nozzle, a lamp socket mounted forwardly of the motor housing and rearwardly of the foremost part of said casing structure, a lamp carried by said socket, a reflector located rearwardly of the axis of said lamp socket and having vertical edge portions spaced from the casing structure and defining therewith a pair of guideways, and a lamp guard having tongue portions adapted to be received in said guideways to removably secure the guard to the casing structure.

2. In a portable suction cleaner, a unitary casing structure comprising a suction nozzle, fan case and motor housing with a suction mouth and a discharge outlet, the interior of said casing being otherwise substantially closed to the atmosphere, said casing structure having a removable section with light-transmitting provisions defining an exterior lamp compartment or cavity closed off from the interior of the casing structure and located forwardly of the motor housing and above and behind the suction mouth of the cleaner, said motor housing and said removable section provided with vertically extending overlapping portions to provide separation between said section and housing upon relative vertical movement, a lamp in said lamp compartment for illuminating the space in front of the cleaner, and means for connecting said lamp to a source of electric current.

3. In a portable suction cleaner, a unitary casing structure comprising a suction nozzle, fan case and motor housing with a suction mouth and a discharge outlet, the interior of said casing being otherwise substantially closed to the atmosphere, said casing structure having a removable section with an imperforate top part and light-transmitting provisions therebeneath defining an exterior lamp compartment or cavity closed off from the interior of the casing structure and located forwardly of the motor housing and above and behind the suction mouth of the cleaner, a member carried by said motor housing having vertical edge portions spaced from the housing and defining therewith a pair of guideways, said removable section having tongue portions adapted to be received in said guideways to removably secure the section to the housing, a lamp in said lamp compartment for illuminating the space in front of the cleaner, and means for connecting said lamp to a source of electric current.

JOHN J. McCABE.

ARTHUR W. SEYFRIED.
